Attorney

UNITED STATES PATENT OFFICE.

PAUL FREYHOLTZ, OF FAIRFAX, MINNESOTA.

CLOTHESPIN.

1,348,102.

Specification of Letters Patent. Patented July 27, 1920.

Application filed August 16, 1918. Serial No. 250,184.

To all whom it may concern:

Be it known that I, PAUL FREYHOLTZ, a citizen of the United States, residing at Fairfax, in the county of Renville and State 5 of Minnesota, have invented new and useful Improvements in Clothespins, of which the following is a specification.

This invention relates to clothes pins, particularly to that type adapted to remain 10 permanently upon a line, and has for its object the provision of a clothes pin including a pair of hingedly connected members which are spring pressed to exert a clamping action upon an article disposed between 15 them, one of the members being provided with a peculiarly constructed end portion providing attaching means whereby it may be permanently supported upon a clothes line.

20 An important object is the provision of a device of this character in which the attaching member adapted for engagement upon the clothes line is formed integrally upon the associated member and comprises 25 merely a reduced extension which is reflexly bent upon itself and engages within an opening formed in the associated member.

20 A further object is the provision of a device of this character which is extremely simple in construction, easy to use, efficient in service, durable in use and a general improvement of the art.

With the above and other objects and advantages in view, the invention consists in the details of construction to be hereinafter more fully described and claimed, and illustrated in the accompanying drawing in which:—

40 Figure 1 is a perspective view of the device suspended from a line.

Fig. 2 is a longitudinal sectional view.

Fig. 3 is a perspective view of one member and

45 Fig. 4 is a perspective view of the other member.

Referring more particularly to the drawing the letter A designates a line from which my device is adapted to be suspended. My 50 improved clothes pin is designated as a whole by the letter B and comprises a pair of members 6 and 7 formed preferably of metal. The member 6 is formed from a flat plate 7^a which has one end curved as shown 55 at 8 and rolled upon itself to provide a bead 9. The side edges of the plate 7^a are bent

onto the plate to provide strengthening flanges 10 and these flanges 10 are cut away at their intermediate portions as shown at 11 to provide ears 12 which extend at right angles to the plate 7 and which are provided with holes 13.

The member 7 is very similar in construction to the member 6 and comprises a plate 14 which has one end curved as shown at 15 and rolled to provide a bead 16. This plate 14 is provided at its sides with flanges 17 which are cut away at their intermediate portions to provide ears 18 extending at right angles to the body of the plate and 70 provided with holes 19.

The members 6 and 7 are disposed in such relation to each other that the ears on the members 6 will be disposed in straddling relation to the ears on the member 7, these 75 ears being pivotally connected by means of a pintle 20 about which is disposed a coiled spring 21, having its ends disposed against the members 6 and 7 as shown. It will be noted that the bead 9 on the member 6 is disposed nearer to the pivot point of the members than the bead 16 on the member 7 so that these beads will be in overlapping relation. The action of the spring 21 is such that the beaded ends of the members 6 and 7 will be urged toward each other 80 for exerting a clamping action upon an article disposed therebetween.

In order to provide means whereby the device may be suspended from a line, I provide upon the other end of the member 7 a reduced extension 22 formed integrally thereon which is reflexly bent upon itself as shown at 23 to provide a loop engageable upon the line A and which has its end portions passed through a slot 24 extending transversely of the plate 14 adjacent its upper end. The end of the extension 22 after being passed through the slot 24 bears firmly against the rear side of the plate 14 and 95 forms a strong structure.

From an inspection of Fig. 1 of the drawing the use of the device will be apparent and it will be seen that it is suspended from the line A by means of the loop 23 which engages thereupon. Articles to be held are merely clamped between the beaded ends of the plates as will be obvious.

From the foregoing description and a study of the drawings it will be apparent 110 that I have thus provided a very simple clothes pin which is adapted to remain

permanently upon a line and which is adapted for supporting any desired articles therefrom in an efficient manner. It will of course be understood that the device is formed of some such material as will not rust or otherwise corrode under the influence of the weather. It will be further apparent that the device is extremely simple and can be constructed of such material as

10 to insure great durability.

Having thus described my invention I claim:—

A clothes pin comprising a pair of members each formed as a plate terminating at

one end in a rolled edge, ears on the side 15 edges of the said plates intermediate the ends thereof and pivotally connected, a spring disposed between and engaging said plates for urging said rolled edges into clamping engagement, and a reduced extension formed on the other end of one of said plates and reflexly bent to provide an attaching loop whereby to provide suspension means for supporting the device from a clothes line, the axis of said loop being 20 25 parallel with said rolled edges.

In testimony whereof I affix my signature.

PAUL FREYHOLTZ.
